CLAIM

The ornamental design for a storage panel for tools and tool holders, as shown and described.

DESCRIPTION

FIG. 1 is a top view of a storage panel for tools and tool holders, showing the ornamental design;

FIG. 2 is a bottom view thereof;

FIG. 3 is a perspective view thereof;

FIG. 4 is a cross-sectional view thereof taken along line 4-4 of FIG. 1;

FIG. 5 is a side view of the storage panel of FIG. 1, the opposite side being identical; and,

FIG. 6 is an end view thereof, the opposite end being identical.

The broken line showing of a storage panel for tools and tool holders is for purpose of illustrating portions of the article and forms no part of the claimed design.
